UNITED STATES PATENT OFFICE.

HENRY F. NEWBURY, OF NEW YORK, N. Y., ASSIGNOR TO ELEVATOR SUPPLY & REPAIR COMPANY, A CORPORATION OF ILLINOIS.

ELEVATOR SIGNAL SYSTEM OR APPARATUS.

1,112,379.

Specification of Letters Patent.

Patented Sept. 29, 1914.

Application filed October 14, 1911. Serial No. 654,637.

To all whom it may concern:

Be it known that I, HENRY F. NEWBURY, a citizen of the United States, residing in the borough of Brooklyn, city of New York, 5 and State of New York, have invented a new and useful Elevator Signal System or Apparatus, of which the following is a full, clear, and exact description.

This invention relates to signal systems 10 such as employed in the operation of elevators.

A principal object of the invention is to provide simple means whereby a passenger 15 intending to take a car from a floor may give a signal to all the cars which are approaching that floor and going in the desired direction.

A further object of the invention is to enable a signal to be given at the floor where 20 the passenger is standing indicating to him which cars are approaching that floor and going in the desired direction.

Further objects of the invention will appear hereinafter.

25 The invention consists in the general combination of parts and simplicity of details hereinafter described, all of which contribute to produce efficient signal apparatus.

A preferred embodiment of my invention 30 will be particularly described in the following specification, while the broad scope of my invention will be pointed out in the appended claims.

In the drawings, Figure 1 is a diagrammatic view illustrating an application of the 35 invention, certain parts being broken away; Fig. 2 is a horizontal cross-section through the signal apparatus which may be employed, with the invention and located on 40 the cars; Fig. 3 is a detail.

In the drawings to which I now refer, like 45 letters of reference designate corresponding parts in the different figures. In the preferred embodiment of the invention here shown, A, A' indicate the cars in which signal devices B, B' for signaling to the operators of the cars are placed. In the preferred form of the invention I provide 50 means corresponding to each floor and to all the cars in the elevator system for controlling the signals. This means preferably consists of bars or controllers C, C', C², C³, by which the signals for the floors such as the two floors indicated may be "set" to 55 enable a signal to be given; the controllers

C and C' are for the upper floor, the controller C corresponding to the up direction of movement, while the controller C' corresponds to the down direction of movement. The corresponding controllers for the lower 60 floor are indicated by C² and C³.

In the preferred form of the invention I provide means for coöperating with these controllers to give the signal if the controllers are set. For this purpose I prefer to 65 provide travelers or carriages corresponding respectively to each elevator and moving correspondingly with each elevator. These travelers are indicated by D and D'. These travelers are preferably driven through any 70 suitable reducing mechanism so that their movement is much reduced though corresponding to the movement of each car. As here shown, the traveler D is supposed to be moving in an upward direction, and traveler D' is supposed to be moving in a downward direction, each car and traveler moving independently of every other car and traveler. These travelers are preferably mounted in suitable guideways such as 75 80 those indicated, and each traveler is guided thereby against movement in a sidewise direction.

The bars, carriers or "controllers", as C, C', etc. are movable in an endwise direction 85 to a limited extent, and preferably they are movable into the "set" condition or position my means of an electro magnet, circuit, switch or push button and source of electricity, the circuit preferably being what is 90 commonly known as an open circuit and the source of electricity, a battery. There is an electro magnet, circuit and passenger's button such as a push button for each bar or "controller". Upon pressing the push button P² to energize the magnet M², the armature m² is attracted and the "controller" C² is moved from its normal condition or position against the stress of the spring S² into the "set" condition or position indicated, 100 105 and in which it is held by the detent device E², composed preferably of a spring portion and a dog adapted to hold the controller in the set position. In order to restore each bar from its set position to its natural position I prefer to provide a spring-pressed pawl I I', arranged so as to be readily movable upon the part F, on carriage D as it moves in one direction, but arranged so as to be held rigid therewith as 110

such part moves in the opposite direction. As the traveler D and part F move in the direction of the arrow the part I' is held rigid with the part F and the pawl I', engages with the roller, as c^4 , attached to the controller, as C^2 , and forces the controller endwise; the spring of the detent device, as E^2 , yields upwardly permitting the dog portion of such device to pass underneath the spring portion, when the stress of the spring S^2 will continue the endwise movement of the controller until it reaches its normal position. In the embodiment shown the function of the detent device E' or E^2 is to hold its controller in the "set" condition or position and the function of the parts, as I' or I^2 , and, as c^3 or c^4 is to release the controllers from the action of their respective detents, as E, E' , etc. and permit the springs S' or S^2 , to restore the controllers to the normal positions, in which they are held against accidental displacement by the springs.

Each of the controllers, as C, C', etc. preferably carries, besides the parts or rollers, c , c' , c^2 , etc. switch devices, as H, H', H ^{2} , etc. each of which is preferably composed of two parts, a movable lever and a pair of contacts which coact together to close a normally open circuit. These spring terminals are pressed together by moving the lever against them, which is preferably accomplished by the action of cam surfaces, as G, G', G ^{2} , etc., on the travelers D and D', respectively. As the travelers D and D' move in their ways or guides the outermost ends of the cams F and F', contact with the levers and turn them on their fulcrums or pivots and move them thereon, as shown at switch device H ^{3} and H ^{6} . When the traveler D' is moving in the direction shown by the arrow thereon the lever h ^{6} is moved toward the spring terminals, as h ^{7} , and the circuit is closed. When the traveler D is moving in the opposite direction, as indicated by the arrow thereon the lever, as h ^{12} swings on its pivot away from the spring contacts or terminals, which are not disturbed, hence the circuit remains open and its signal device inoperative. This construction provides for the closing of the spring terminals of each one of the switch devices in only one direction of the movement of its coacting traveler. These switch devices, as H, H', H ^{2} , etc., are arranged, with the controllers on which they are mounted, for giving "up" and "down" signals at each of the intermediate floors of the building as desired, there usually being one switch device for each direction of movement of each elevator car at each of such floors.

The rollers c , c' , c^2 and c^3 are mounted on fixed pins on the sides of the controller bars and may be disposed adjacent to the levers 65 such as the levers h but are not connected

in any way with these levers. As the cars move in the "up" or the downward direction the corresponding "up" or "down" switch levers are actuated.

Each switch device is connected with a signal device by a circuit and source of electricity. The floor signal devices are usually over the door of the shaft, there being an "up" and "down" signal device for each intermediate floor of each elevator shaft for signaling to the intending passenger which of the elevator cars is the first to approach the floor in the direction for which the signal was "set," that is the direction the passenger desires to go. The switch levers, as h, h ^{1} , h ^{2} , etc. can only be actuated when the bars or "controllers" on which they are mounted are in "set" position for the reason that when the "controllers" are in the normal position the switch levers are out of the paths of the cams F, F'.

In the preferred form of the invention means is provided whereby the movement of a controller bar effects the closing of the signal circuit. To this end each of the bars or "controllers," as C, C', C ^{2} , etc. carries in addition to the switch devices, as H, H', H ^{2} , etc., one member or contact of another form of switch device, as J, J', J ^{2} , etc., the other member or contact of which is preferably secured to the frame of the apparatus, the two parts being so arranged that when the bars or "controllers" are in their normal condition or position, the contacts are separated from one another, but when the "controllers" are in the "set" or signal giving position or condition they are in contact. Each of these switch devices, as J, J', J ^{2} , etc., is connected by a circuit with a signal device O in each of the cars and a source of electricity, as Z ^{3} , so that a signal may be given in each car, whatever its position may be, upon the contact of the two members of any one of the switch devices.

There is preferably an "up" and a "down" signal device in each car for each intermediate floor. Each of these signal devices, as O, consists of an electro magnet, as o, an armature as o', and a movable cap or cover, as o ^{2} , with a suitable opening as o ^{3} , in the front of the casing, as B or B', which opening is preferably filled with glass or other transparent substance. In the casing, as B or B', there is placed means for giving a continuous light, preferably any suitable incandescent lamp or lamps. Thus a single incandescent lamp may serve for giving both "up" and "down" visual signals for many floors instead of a lamp for each "up" and "down."

Switch device J has a circuit composed of wire 1 leading from the movable terminal thereof on the controller C to the source of energy, as Z ^{3} , thence by wire 2 to and

through the "up" signal electro magnets for that controller and switch device in each elevator car and thence back to the stationary terminal therefor. The circuit for switch device, such as J' , consists of the wire 3 leading from the movable terminal thereof to the source, as Z^3 and thence through the electro magnets o of the "down" signal devices of controller C' by wire 4 to the fixed terminal of switch device, as J' . Likewise the circuit for switch device, as J^2 , consists of the wire 5 leading from the movable terminal thereof and connecting with wire 1 which leads to the source Z^3 , thence from such source to and through the electro magnets, as o , of the "up" signal device in each of the cars for the controller C^2 by wire 6 back to the fixed terminal of switch device, as J^2 . The circuit for switch device, as J^3 , consists of the wire 7 leading from the movable terminal of that device to and connecting with the wire 3 leading to the source Z^3 , thence to and through the electro magnets, as o , of the "down" signal devices in each of the cars for that controller by wire 8 back to the fixed terminal of switch device, as J^3 . The circuits by which the controllers or bars, as C , C' , C^2 , etc. are moved from their normal or inoperative condition or position to the "set" or operative condition or position are as follows, there being a circuit for each controller or bar with a switch or push button device therein. Each controller or bar is arranged in such relation to an elbow lever having an armature, as m , m' , m^2 , etc. attached thereto and an electro magnet as M , M' , M^2 , etc. that when the circuit is closed its respective magnet is energized and the elbow lever moved on its fulcrum and the controller is moved from its normal to its "set" or operative condition or position and its respective switch device, as J , J' , J^2 , etc. is closed and the respective "up" or "down" electro magnets, as o , of the signal devices in each of the plurality of cars is energized and the respective caps or covers as o^2 , of such devices are operated by the armatures to which they are attached being attracted thereby, exposing the respective openings, as o^3 , thereof to the light of the lamp, as N , in each casing, as B or B' . The circuit for controller C , as shown, consists of the wire 11 leading from the switch or push button device, as P , to the electro magnet M and thence by wire 12 back to source Z and push button device P . The circuit for controller C' leads by the wire 13 to electro magnet M' and thence back through source Z to the push button device P' by wire 14. The circuit for controller C^2 consists of the wire 15 leading from source, as Z' , to push button device P^2 and thence by wire 16 to electro magnet M^2 .

and back to source Z' , by wire 17. The circuit for controller C^3 leads from source Z' by wire 18 to electro magnet M^3 and thence to push button device P^3 by wire 19 and thence to source Z' by wire 15, as shown.

The lamps, as N , in each car are preferably placed in one circuit, as shown, and connected with a source of electricity, as Z^2 , which may be common to other lamp circuits, if desired, also as shown. The circuit connecting these lamps with the source, as Z^2 , is normally closed during the use of the signal devices and elevator cars. The circuit consists of the wire 9 leading from the lamps, as N , in each car to the source, as Z^2 , and thence by wire 10 back to the lamps, as shown. The switch devices, as H , H' , H^2 , etc. are each, as shown, substantially duplicates of one another.

The lever, such as h , which closes the switch has mounted thereon a two arm spring, as x , seen in Fig. 3 wherein the lever is shown on a somewhat enlarged scale to better show the relation of the parts. This two arm spring, as x , always tends to hold the lever, as h , in a horizontal position, or substantially parallel with the controller, as C , consequently, the stress of such spring returns such lever to such position whenever moved in either direction by the movement of the carriage.

The circuits for the floor signals at the door of each elevator shaft on each of the floors by which the intending passenger is signaled which is the first approaching car going in the direction he signaled he desired to go are as follows; a wire 20 leads from the device H to the signal light L and thence by wires 21 and 10 to the source Z^2 and thence by wires 9 and 22 to switch device H , thus connecting the spring terminals, as h' , with signal L and source Z^2 ; a wire 23 leads from the switch device H' to the signal light L' and thence by wire 24 to source Z^2 and thence by wire 25 back to switch device H^1 ; a wire 26 leads from the switch device H^2 to signal light L^2 , thence by wires 27, 21 and 10 to source Z^2 and thence by wires 9 and 28 back to switch H^2 ; a wire 29 leads from switch device H^3 to signal light L^3 , and thence by wires 30 and 24 to source Z^2 and thence by wires 25 and 31 back to switch H^3 ; a wire 32 leads from switch device H^4 to signal light L^4 and thence by wires 33, 21, 27 and 10 to source Z^2 and thence by wires 9 and 34 back to switch H^4 ; a wire 35 leads from switch device H^5 to signal light L^5 , thence by wires 36 and 24 to source Z^2 and thence by wires 25 and 37 back to switch H^5 ; a wire 38 leads from switch device H^6 to signal light L^6 , thence by wires 39, 21, 27 and 10 to source Z^2 , and thence by wires 9 and 40 back to switch H^6 ; and a wire 41 leads from switch

device H' to signal light L' , thence by wires 42 and 24 to source Z^2 and from thence by wires 25 and 43 back to switch device H' .

In the embodiment of my invention herein shown if the "up" button, as P , be momentarily operated the electromagnet, as M , will be energized, its armature, as m , attracted, moving the elbow lever connected therewith and forcing the controller, as C from its 10 normal or inoperable condition or position into its "set" or operable condition or position where the switch devices, as H and H' , can be operated by the upward movement of one of the respective carriages, as D and D' , 15 the first carriage passing the controller operating its switch device and restoring the controller, with its switch devices, to the normal or inoperable condition or position. In addition to the movement of the controller into its "set" or operable condition or position for giving the signal to the intending passenger by magnet M and armature m such controller, carrying the movable member of the switch device J , moves such movable member into contact with its fixed member thereby closing the circuit and operating the "up" signal devices corresponding to that floor in all of the elevator cars, thus signaling the operator of each car that 20 a person is at that instant waiting at that floor to be taken aboard by the first approaching car, and has also "set" the controller so that such person will be signaled which one of the plurality of cars is the 25 first to approach the floor in the direction he signaled he desired to go. The restoring of the controller to its normal or inoperable condition or position by the movement of the carriage past it, as heretofore explained, 30 breaks the circuit at the device J and the electromagnets o of the "up" signal devices in all of the cars are deenergized and the openings o^3 in the cases, as B and B' , are closed by the caps or covers o^2 by means of 35 the usual springs commonly used to return armatures to their normal positions.

It will thus be seen that the operator of each of the plurality of cars is simultaneously signaled at the instant that the push button device is operated by reason of the closing of any one of the switch devices, as J , J' , etc. and movement of its respective controller and that such signaling continues until the first one of the plurality of cars 50 going in the direction the passenger signaled he desired to go reaches the floor from which the signal was given. Also that upon so operating such push button device the respective floor signal for the passenger is 55 "set," or brought into operable condition, or moved from its normal or inoperative position to its operative position or condition, ready for the first approaching car, going in the direction signaled, to operate such 60 floor signal when such car has reached a 65

predetermined point in its travel relatively to such floor, also that such car as it passes onward in its direction of travel the carriage as D or D' , engages with the roller of the controller of the operating means whose 70 push button device was so operated and moves such controller in an endwise direction sufficiently to release the controller from its detent device, as E , E' , etc. and permit the spring, as S , S' , etc. to continue the 75 endwise movement of such controller until it and its several switch devices are restored or returned to their normal or inoperative position, and the signal devices cease to operate.

It is understood that the embodiment of the invention described above is only one of the many embodiments or forms the invention may take, and I do not wish to be limited in the practice of the invention nor in my claims to the particular embodiment set forth.

What I claim as new is:

1. In an elevator signal apparatus, in combination, a plurality of cars, a passenger's button, a movable member, and means whereby said member is adapted to be displaced by the operation of said button, said movable member corresponding to the said button and corresponding to all the said 90 cars in common, floor-signal circuits including floor signals for indicating the direction of movement of said cars, means moving correspondingly to said cars and coöperating with said movable member to close said 95 floor signal circuits, and a car signal circuit including signals in the cars, and means for closing said car signal circuit through the medium of said movable member.

2. In an elevator signal apparatus, in combination, a plurality of cars, a passenger's button, a movable member, and means whereby said member is adapted to be displaced by the operation of said button, said movable member corresponding to the said 100 button and corresponding to all the said cars in common, floor signal circuits including floor signals for indicating the direction of movement of said cars, means moving correspondingly to said cars and coöperating with said movable member to close said 105 floor signal circuits, a car signal circuit including signals in the cars, means for closing said car signal circuit through the medium of said movable member, and means 110 for returning said movable member to open said car signal circuit when any car arrives at a predetermined point.

3. In an elevator signal apparatus, in combination, a plurality of cars, a passengers' button, a movable member, and means whereby said member is adapted to be displaced by the operation of said button, said movable member corresponding to the said 125 button and corresponding to all the said cars 130

in common, floor-signal circuits including floor signals for indicating the direction of movement of said cars, means moving correspondingly to said cars and coöperating with said movable member to close said floor-signal circuits, and arranged to return said movable member, and a car signal circuit including signals in the cars, and means for closing said car signal circuit through the medium of said movable member.

4. In an elevator signal apparatus, in combination, a plurality of cars, a passengers' button, a movable member, and means whereby said member is adapted to be displaced by the operation of said button, said movable member corresponding to the said button and corresponding to all the said cars in common, floor signal circuits including floor signals for indicating the direction of movement of said cars, means moving correspondingly to said cars and coöperating with said movable member to close said floor signal circuits, a car signal circuit including signals in the cars, means for closing said car signal circuit through the medium of said movable member, means for returning said movable member to open said car signal circuit when any car arrives at a predetermined point, and means for yieldingly holding said movable member in its normal position and yieldingly in its displaced position.

5. In an elevator signal apparatus, in combination, a plurality of cars, a passengers' button, a movable carrier, and means whereby said carrier is adapted to be displaced by the operation of said button, said carrier corresponding to the said button and corresponding to all the said cars in common, floor signal circuits including floor signals, circuit-closers therefor carried by said mov-

able carrier and travelers moving correspondingly to said cars and adapted to actuate said circuit-closers to close said floor signal circuits, car signal circuits including signals in the cars and means for closing the same through the agency of said carrier.

6. In an elevator signal system, in combination, a plurality of cars, a passengers' button, a movable member, and means whereby said member is adapted to be displaced by a movement of said button, and corresponding to all the cars, a signal circuit to the cars, and means for closing said circuit through the agency of said movable member and the opening of said circuit through the movement of the said cars.

7. In an elevator signaling apparatus in combination, a car, a movable member corresponding to a floor and corresponding to one direction of movement for said car, a second movable member corresponding to another floor and corresponding to the same direction of movement of said car, a passenger's button at each floor, and means whereby the said member corresponding to that floor is adapted to be displaced by the operation of its corresponding button, a signal circuit corresponding to each floor normally open at a single point and including a signal in the car corresponding to that floor and arranged to be closed by the displacement of the corresponding movable member, a floor signal circuit including a floor signal for each floor, and a traveler moving correspondingly to the car and coöperating with the movable member corresponding to that floor to close the floor signal circuit.

Correction in Letters Patent No. 1,112,379.

It is hereby certified that in Letters Patent No. 1,112,379, granted September 29, 1914, upon the application of Henry F. Newbury, of New York, N. Y., for an improvement in "Elevator Signal Systems or Apparatus," an error appears in the printed specification requiring correction as follows: Page 1, line 88, for the word "my" read *by*; and that the said Letters Patent should be read with this correction therein that the same may conform to the record of the case in the Patent Office.

Signed and sealed this 20th day of October, A. D., 1914.

[SEAL.]

J. T. NEWTON,
Acting Commissioner of Patents.
